CLAIM

I claim the ornamental design for a light emitting diode module, as shown and described.

DESCRIPTION

FIG. 1 is a perspective view of a light emitting diode module according to my new design;

FIG. 2 is a front view of the same module, a rear view being identical to the front view;

FIG. 3 is a right side view of the same module, a left side view being identical to the right side view;

FIG. 4 is a top plan view of the same module; and,

FIG. 5 is a bottom view of the same module.
